Primary Examiner — Darlington Ly(74) *Attorney, Agent, or Firm* — Birch, Stewart, Kolasch & Birch, LLP(57) **CLAIM**

The ornamental design for a steering wheel for automobile, as shown and described.

DESCRIPTION

1. Steering wheel for automobile

1.1 is a perspective view of a steering wheel for automobile embodying our new design;

1.2 is a front elevation view thereof;

1.3 is a rear elevation view thereof;

1.4 is a left side elevation view thereof;

1.5 is a right side elevation view thereof;

1.6 is a top plan view thereof;

1.7 is a bottom plan view thereof; and

1.8 is a front elevation view thereof in which an exemplary graphical user interface is displayed on its screen and represents a state of use.

The parts shown by means of broken lines in the reproductions are not part of the claimed design.

1 Claim, 8 Drawing Sheets(56)
